Filed Mar. 16, 1962, Ser. No. 180,169
7 Claims. (Cl. 189—2)

This invention relates to ground anchoring arrangements for building structures. More particularly, this invention relates to improved ground anchoring arrangements for geodesic building structures of the type disclosed in my previously filed application, Serial No. 676,223 which matured as Patent No. 3,026,651 on March 27, 1962, filed August 5, 1957.

Accordingly, it is a primary purpose of the instant invention to provide a ground anchoring arrangement for a building structure of the type shown in the aforesaid patent application wherein improved means are utilized to secure the building structure to the ground.

Other purposes and advantages of the instant invention will become more apparent from a review of the following detailed description when taken in conjunction with the appended drawings, wherein:

FIG. 1 is a schematic view of a geodesic dome structure, the base perimeter of which can be anchored to the ground by the anchoring means of the instant invention;

FIG. 2 is a fragmentary perspective view of a portion of the base perimeter of the building structure shown in FIG. 1 and discloses in more detail the unique arrangement for anchoring the building structure to the ground;

FIG. 3 is a view with parts added and generally taken along line 3—3 of FIG. 2; and

FIG. 4 is an exploded view of the flanged column elements, etc., making up the ground anchoring arrangement of the instant invention.

With further reference to the drawings and in particular FIG. 2, the base perimeter anchoring means of the instant invention can be advantageously employed with the type of geodesic structure generally disclosed in my previously filed patent application Serial No. 676,223, filed August 5, 1957, wherein specially formed panels are employed. Since the structure of these panels and the manner in which they are secured together is fully disclosed in my previous application, no detailed discussion of the same is believed to be required.

The geodesic building structure, as indicated in FIG. 1 is generally made up of a plurality of panel members or structural units 2. These panels are four-cornered and are so formed that they are preferably diamond-shaped in plan and have a major axis MM and a minor axis NN. The structural unit or panel includes corners or vertices 3, 4, 5 and 6, the corners or vertices 3 and 4 lying along the major axis and corners 5 and 6 lying along the minor axis. Corners 5 and 6 are also displaced upwardly from the normal plane of rest of the sheet and, in turn, are connected by suitably shaped strut members 7 which lie along and generally coincide with the minor axis NN. The strut 7 is secured to a panel 2 by means of an apertured sleeve member which fits over the end of the strut or the ends of the strut can be provided with apertured flanged portions 8. Bolts or rivets (not shown) pass through suitable openings in the flanged portions 8 and corresponding openings in the panel adjacent the corners 5 and 6.

The sheet or panel 2 can also be advantageously pro-

2

vided with a plurality of delineations or creases 12 and 13, emanating from the major axial points or vertices 4 and 3 of the sheet.

The marginal edges of a structural unit or panel 2 are provided with reinforcing marginal flanges 9 which act as integrally formed frame elements for a building structure in which the panels 2 are incorporated.

As indicated in my previous application, the formed panel along with its strut 7 defines a tetrahedron-like solid or building block wherein certain integral portions of the panel serve as a framework while other integral portions of the panel serve as a covering for the building in which they are incorporated.

When one structural unit 2 is joined to another structural unit or panel 2 to form a series of building blocks, each panel, in effect, serves as a three-dimensional beam unit in a three-dimensional space truss structure. The mathematical arrangement of these structural units is such that load stresses are distributed substantially 10 through all of the material in each unit and are directed to the diamond vertices or tips 3, 4, 5 and 6. These tetrahedron-like elements are of considerable three-dimensional strength and the central portion of a panel 2 located along the line or plane MM, i.e., a long diagonal, 15 also advantageously acts in the manner of a strut or frame member.

When a plurality of the units 2 including a strut 7, are joined at a common point X, six of the units having adjacent flanged edges are located in abutting relation 20 30 while the struts 7 of each of the six units are joined together and approximately define a regular hexagon, all as described more fully in my previous application.

To the aforesaid basic pattern there may be added 35 additional series of structural units so arranged that the struts 7 are connected to the various vertex points B which comprise the conveying points of the short diagonals of the various four-sided and four-cornered panels.

By securing the panels together in this fashion along 40 with the struts 7 and the short diagonals thereof, the struts on adjacent units are also interconnected with each other, whereby the struts advantageously transfer loads from one to the other. By use of the structural panels herein described, the unique structure, as formed, has a 45 geometrically patterned spider-like framework comprised of struts 7 and a surface wall of undulating marginally joined four-sided sheets. The geometric pattern or frame is generally a series of re-occurring hexagons. The total 50 arrangement of the panels becomes that of a hexagonal strut overlying a three-dimensional covering of bowed panels 2. The structure formed from these panels 2 is also geodesic in that the vertices of all tetrahedron-like building blocks or structural elements 2 fall in a 55 series of great circles which generally define a sphere in the case of the building structure shown in FIG. 1. In the building structure as shown in FIG. 1 each strut 7, the long and short diagonals and the marginal flanges 9 of any two contiguous units are positioned along great circle arcs.

The novel arrangement for anchoring a structure as 60 shown in FIG. 1 to the ground will now be described. As illustrated, particularly in FIGS. 2—4, this arrangement contemplates that the bottom extremities of a plurality of panels located adjacent the bottom perimerical 65 portions of the building structure will be directly anchored to a series of base supports or ground piers 14. Base perimeter portions of the building are connected

to piers 14 through the use of unique flanged columns 16.

Each of the flanged columns is generally comprised of a web or base 17 and sides 18. Each of the sides 18 is further provided with outwardly and somewhat downwardly disposed flange members 19. The sides 18 project in a converging fashion with web 17 from one end 20 of the flanged column until they merge with the web 17 and flanges 19 adjacent the other extremity 21 of the flanged column. Thus, the other extremity 21 of the column is somewhat triangular in cross-section.

The inclined flanges 19 of the flanged column 16 which are also generally of triangular shape in plan are each secured to a marginal side edge of a separate panel 2 in such a fashion by bolts or rivets 22 that the lower extremity 20 of the flanged column 16 is affixed to a vertex or tip 3 located along the major axis of a panel 2 while the upper portion or extremity 21 is located or secured to contiguous panels 2 adjacent a vertex point 5 and 6 of the panels 2 which fall along the minor axis thereof. Stated another way, each flanged column is secured adjacent to the contiguous side marginal edges of a pair of contiguous panels 2, such that the one extremity 21 of a flanged column 16 is secured to panels 2 adjacent the upwardly displaced corners and the minor axis thereof, while the other or lower extremity of the column 16 is secured to the portions of the panel units 2 which are located along the major axis of the panels. This same lower portion of the flanged column is also the part of the column which is directly secured to an anchoring pier 14 by means of an apertured anchoring cap 23. Anchoring cap 23 is a generally channel-shaped member which fits over and is welded to the bottom extremity 20 of column 16. Affixed to each of the sides 24 of the cap 23 is a fitting 25. Fitting 25 includes an angular portion 25' welded or otherwise secured to cap 23 and a tongue portion 26 bolted to the underside of a panel 2. It is to be understood, of course, that the two contiguous panels 2 to which the flanged column 16 is attached are secured together by means of rivets or bolts 27 passing through their contiguous flanges 9.

The flanged column is affixed to a pier 14 by fitting the capped lower portion of the flanged column 16 over the upwardly projecting shoe element 28 mounted within bracket 29, bracket 29 in turn being secured to the top of concrete pier 14 through the medium of bolt members 30 and leveling plate 31. As the cap 23 and column 16 are fitted over the shoe 28, the hole 33 of shoe 28 is aligned with openings 34 in cap 23 and openings 35 in the sides 18 of the column 16 and a bolt 36 is then thrust through these openings and locked in place.

It will be further noted that, if desired, the strut member 7 can be omitted from the panels to which a flanged column 16 is attached. In the case where the strut is employed with the panel members, it is to be observed that the upper extremity of the flanged column 16 terminates adjacent to but short of the vertices 5 and 6 so as not to interfere with the normal attachment of a strut to a panel member.

If desired, filler panel segments 40 may be disposed intermediate the piers 14, to which the flanged columns 16 are secured. In such instances, the extremities of the filler panel segments 40 would be suitably connected to the angular portions 25' of the fittings 25 by bolt means, etc. (not shown).

It will be observed that the flanged column 16 advantageously forms continuations of the struts on certain of the panels or units used in the building structure. Thus, they form, in effect, continuations of the geodesic arcs or circles formed by these struts.

An advantageous embodiment of the invention has been disclosed and described. It will be appreciated that various changes can be made in the described invention which are within the scope thereof, the invention being limited only as defined in the following claims, wherein what is claimed is:

1. In a building structure comprised of a plurality of structural units said units each comprising a four-cornered sheet, said sheet being bowed such that two opposing corners thereof are displaced upwardly from the normal plane of rest of said sheet and a strut extending across said sheet and connected solely at its ends to said upwardly displaced corners, the marginal edges of said sheet being flanged and said units being connected together in a fixed geometric pattern such that a series of regular polygons are formed by said struts, means anchoring the base perimetrical portions of the building structure formed from said units to ground piers, said means including a column provided with flanges affixed to a pair of contiguous structural units located adjacent the base perimeter of the building structure, one extremity of the column terminating adjacent the displaced corners of said pair of units and the other extremity of the flanged column being affixed to a pier, the flanges of the column overlying and being affixed to the said pair of units adjacent the contiguous side edges of said units.

2. In a structure as set forth in claim 1, wherein the flanged column of said anchoring means is aligned with the strut of a further unit, the displaced corner of said last-mentioned unit mating with the displaced corners of the said contiguous pair of units.

3. In a structure as set forth in claim 1 wherein said anchoring means further includes shoe means affixed to a pier, a cap means affixed to the last-mentioned extremity of the flanged column and said cap means also being affixed to said shoe means.

4. In a building construction a plurality of structural units so disposed and secured to each other as to form a three-dimensional space truss, each of said units comprising a four-cornered panel, said panel in turn being bowed about an axis coinciding with a diagonal center line in the said panel, such that two opposing corners thereof are displaced upwardly from the normal plane of rest of the panel, the panels being secured together in a fixed geometric pattern, means anchoring the base perimetrical portions of the building formed from said panels to base supports, said means including a flanged column, the flanges of said flanged column overlying and being affixed to a pair of contiguous panels located adjacent the base perimeter of the building and adjacent the contiguous marginal edges thereof, one extremity of the flanged column terminating adjacent certain displaced corners of the pair of contiguous panels and the other extremity of the flanged column being affixed to a base support.

5. A building structure as set forth in claim 4 wherein said anchoring means includes shoe means affixed to a base support, a cap means affixed to the last-mentioned extremity of the flanged column, said cap means also being affixed to said shoe means.

6. A building having an outer surface conforming to the contour of a sphere comprising a plurality of panel members of diamond shape, body portions of which serve as a covering for the building and flange portions of which have downturned edges united to form a framework for the building, each of said panel members being bowed such that two opposing corners thereof are displaced upwardly from the normal plane of rest of a panel member, said displaced corners being united by a strut to brace said panel members and the joined flanged portions of the panel members being disposed along the arcs of great circles, means disposed at spaced intervals along the perimeter of the base of said building anchoring the same to a series of ground piers, said means comprising flanged columns, the flanges of each of said flanged columns overlying and being affixed to a pair of contiguous panel members adjacent the contiguous sides of the panel members of said pair of panel members, the upper extremity of each of the flanged columns terminating adjacent a point where certain tips of a group of panel members converge to form a reaction point and the lower extremity

of each of the flanged columns being anchored to a pier to form a continuation of the arc of the great circle formed by portions of certain of the panel members.

7. A building as set forth in claim 6, wherein said anchoring means includes a shoe affixed to each pier and a cap means affixed to the lower extremity of each of the flanged columns, said cap means also being affixed to said shoe.
